WITNESS:

ATTORNEY

UNITED STATES PATENT OFFICE.

NENA M. ADAMS, OF CHICAGO, ILLINOIS.

HAIR WRAPPER.

Application filed May 7, 1926. Serial No. 107,477.

This invention relates to improvements in hair wrappers used for forming waves in ladies' hair.

The principal object of the invention resides in a hair wrapper adapted to form a Marcel wave in the hair, and to simultaneously curl the ends of the hair in the same operation.

Another object of the invention is to provide a hair wrapper which may be easily attached to the hair to be waved and on which the hair can be conveniently wound by the operator for forming either a Marcel wave or an ordinary curl, or both simultaneously.

A further object of the invention resides in the provision of a hair wrapper constructed of a single piece of material and which may be manufactured at a relatively low cost in comparison to those types of hair wrappers now on the market.

With these and other objects in view, the invention resides in certain novel construction and combination and arrangement of parts, the essential features of which are hereinafter fully described, are particularly pointed out in the appended claim, and are illustrated in the accompanying drawing, in which:—

Figure 1 is a perspective view of the hair wrapper per se.

Figure 2 is a similar view but showing the manner of attaching the same to the hair to be wound.

Figure 3 is a side elevation of the wrapper with the hair wound thereon.

Figure 4 is a detail view of a hank of hair after being removed from the wrapper.

Referring more particularly to the drawing, the reference numeral 10 designates my improved hair wrapper in its entirety which is cross shaped in elevation and comprises a longitudinal rod or shank 11, which tapers from one end toward its other end. A pair of oppositely extending arms 12 project outwardly from the shank 11 adjacent the narrow or top end thereof for a purpose to be presently explained. The top end of the shank has an annular groove 13 therein, while the extreme top end of the same is slit to provide right angularly disposed slots 14.

The wrapper may be molded into a single piece and is preferably constructed of light metal so as not to weigh too heavily upon the head when applied thereto for forming the desired waves.

In the operation of the wrapper, a string or flexible element 15 is wound about the hank of hair 16 to be waved adjacent the base of the same, so as to group the hairs, after which the free end of the string is seated in the annular groove 13 on the top end of the shank so that the wrapper is supported from the hank of hair. The free ends of the string are next inserted in the respective slots 14 in the end of the shank so as to prevent unwinding of the string, which would tend to cause the wrapper to become separated from the hair. The hank of hair 16 is wound over and under the respective arms 12 in the manner shown in Figure 3 of the drawing until the length of hair to be marceled is contained on the arms. It is the practice, due to the style of ladies' hair dress to curl the ends of the hair and it is accomplished by winding the free end of the hank about the shank or bar 11 below the cross arm. The usual protecting pad is adapted to receive the wrapper with the hair wound thereon, after which the usual heating element is applied to produce the waves. By reason of the manner of wrapping the hair upon the wrapper, it is possible to form a perfect Marcel wave and curl in less time than those types of wrappers now used for this purpose.

It might be mentioned that either a flat Marcel wave or a round Marcel wave may be formed with this wrapper depending upon the manner in which the hair is wound thereon.

In Figure 4, of the drawing, I have shown a detail view of a hank of hair after the wrapper has been removed and it will be noted that a Marcel wave is formed from the base of the hair outward, while the free ends of the same are curled. By reason of the tapered shank, a similar appearance will be imparted to the curl. If desired, the entire length of hair may be wound about the cross arms to form a Marcel wave for the entire length of the hank, or the entire hank may be wound upon the shank for curling purposes.

While I have described what I deem to be the most desirable embodiment of my invention, it is obvious that many of the details may be varied without in any way departing from the spirit of my invention, and I therefore do not limit myself to the exact details of construction, herein set forth nor to anything less than the whole of

my invention limited only by the appended claim.

It is understood that my hair wrapper is intended for use in connection with permanent waving machines.

What is claimed as new is:—

A hair waving device comprising a longitudinal tapering shank which is round in cross section, oppositely disposed arms extending therefrom adjacent the narrow end thereof; a kerf provided in the narrow end of said shank, and an annular groove pro-

vided in said shank adjacent the said end, said kerf and groove adapted to receive a piece of cord by which the device is attached to the base of a hank of hair to be waved, whereby the hank of hair may be twisted over and under said arms to produce a wave therein, while the free end of the hair is adapted to be wound about said shank to produce a curl therein.

In testimony whereof I affix my signature.

NENA M. ADAMS.
